The ornamental design for a shaving razor container, as shown and described.

DESCRIPTION

FIG. 1 is a front perspective view of a shaving razor container showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is rear perspective view thereof;

FIG. 9 is bottom perspective view thereof; and,

FIG. 10 is a perspective view, shown with exemplary shaving razors.

The broken lines shown illustrate both portions of the shaving razor container and exemplary shaving razors which form no part of the claimed design.
